UNITED STATES PATENT OFFICE

HAROLD WESSON, OF SPRINGFIELD, MASSACHUSETTS, ASSIGNOR TO SMITH AND WESSON, INC., OF SPRINGFIELD, MASSACHUSETTS, A CORPORATION OF MASSACHUSETTS

FLUSH VALVE

Application filed April 22, 1929. Serial No. 356,947.

This invention relates to flush valves and has for its principal object the provision of a simple and economical device for automatically delivering a predetermined volume

5 of fluid to a reservoir such as the basin of a water closet or the like. One particular feature of the invention resides in the provision of an adjustable hydraulic governor, or dash-pot, adapted to retard the closing movement 10 of an outlet valve so that a measured quantity of fluid will pass through the outlet after the mechanism for opening the valve is released. Additional objects reside in the 15 particular structural improvements in the apparatus hereinafter described and pointed out in the appended claims, which furnish a compact and conveniently operated flush valve, usually silent in operation and durable in use.

20 A recommended embodiment of the invention is shown for the purpose of illustration in the accompanying drawings, in which:

Fig. 1 is a central vertical section of the improved valve;

25 Fig. 2 is a section on the line 2—2 of Fig. 1;

Fig. 3 is a transverse section on the line 3—3 of Fig. 1;

Fig. 4 is a central vertical section of the 30 device taken at right angles to that of Fig. 1;

Fig. 5 is an inside end view of the dash-pot adjuster; and

Fig. 6 is a transverse section on line 6—6 of Fig. 1.

35 The structure includes a substantially cylindrical casing 9 having an outlet port 13 in its bottom, a removable cover 11 having an inlet port 10 in one side, and a poppet valve 14 seating in the port 13. A carriage 40 or frame for the valve, comprising top and bottom cross-heads 15 and 16, respectively, and diametrically disposed spacer rods 17, is mounted for sliding movement longitudinally of the casing in a guide plate 18 fixed 45 within the bore of the casing.

The valve 14 is provided on its upper face with a groove loosely to receive the cross-head 16 which is attached by a pin 19 having a loose fit with an opening in the cross-head and a tight fit with aligned openings

in the valve. The valve is thus securely but loosely mounted upon the lifting carriage so that a tight seating of the valve is insured.

The guide plate 18, which is preferably 55 fitted upon an annular shoulder 22 of the casing, is provided with apertures 23 permitting the free and substantially unrestricted passage of water from the inlet port to the outlet port. It will be understood that the 60 water or other fluid enters the inlet under considerable pressure and that the water pressure upon the valve 14 normally holds the valve in seated position over the outlet.

An hydraulic governor is provided to retard the seating movement of the valve, once the latter has been opened. This governor preferably comprises a dash-pot disposed in the path of movement of the valve carriage and may comprise a central cylinder 24 integral with the guide 18 and provided with a vent and check valve 27, and a piston 25 having a stem 28 threaded in the head 15 and suitably fastened to the piston, as by means of the collar 29 pinned to the stem 70 and a retaining spring 30. Sufficient clearance is provided between the cylinder and piston to prevent binding and to permit the slow escape of water as the piston moves 75 downwardly.

The extent to which the piston extends into the cylinder is adjustable, whereby the time of downward movement of the piston may be so regulated that a measured volume of water is delivered through the outlet port before 80 the valve is seated. The preferred construction of the adjusting means comprises a sleeve 20 having ribs 21 punched inwardly to slide in corresponding grooves in the stem 28 so that rotation of the sleeve from outside the casing causes the stem to thread upwardly or downwardly in the cross-head 15. A lock-nut 31 engages a flange on the sleeve to hold the parts in adjusted position.

The mechanism for lifting the valve carriage to open the ball valve preferably comprises a handle 33 and a rotatable shaft 34 mounted in a nipple 35 screwed into the side wall of the casing, the shaft having a cam 36 at its inner end bearing against the under 100

side of a member carried by the carriage, such as the flange 37 of the cross-head 15. A stuffing box 38 may be threaded upon the inwardly projecting end of the nipple 35 to prevent leakage of water around the shaft. The handle is connected to the shaft by a pin 39 extending through slots 40 in the tubular part 41 of nipple 35 which permit limited rotation of the handle to open and close the valve. The handle is automatically restored to normal position by coil spring 42. The nut 43 which closes the end of tube 41 may be provided with a rubber bumper 44 for a toilet seat cover.

15 The operation of the device is extremely simple. The valve is normally closed by pressure of the water and the handle is held in the inoperative position shown in the figures by the spring 42. Movement of the handle 20 then rotates the shaft 34 and the cam 36 lifts the carriage and opens the valve until the cross-head 16 engages the fixed plate 18. As the valve lifts water flows into the cylinder past check valve 27, as well as between the piston and cylinder, thereby permitting the valve to be opened quickly. As soon as the handle is released the valve automatically closes. The closing movement of the valve is retarded by the dash-pot, which insures a 30 slow seating of the valve at a uniform speed depending upon the time required for the water within the cylinder 24 to escape around the piston, as adjusted by regulation of the stem 28.

35 A valve constructed in accordance with the foregoing description is economical to manufacture, easy to assemble and disassemble, and simple to operate; the structure is compact and may be so fashioned as to be attractive in appearance without sacrifice of operative efficiency; and the movable elements are so constructed and arranged that the operation of the valve is extremely quiet and that the possibility of faulty operation is remote. It will be understood, however, that details of construction may be varied for particular purposes without departing from the essence of this invention as defined in the following claims.

40 I claim:

1. A flush valve comprising a casing having a valve seat at one end, a guide in the casing intermediate its ends, a cylinder on the guide having an open end facing away from the valve seat, a carriage having rods sliding in the guide, and cross-heads interconnecting the rods on opposite sides of the guide, a piston mounted on one cross-head to cooperate with said cylinder and a valve on the other cross-head to cooperate with said seat, a threaded stem for adjusting the piston longitudinally of the cylinder, and a sleeve journaled in the other end of the casing for rotating the threaded stem from outside the casing, said sleeve having sliding but

non-rotating relation with the stem, so that the position of said piston may be adjusted without moving the sleeve longitudinally of the casing.

2. A flush valve comprising a casing having a valve seat at one end, a guide in the casing intermediate its ends, a cylinder on the guide having an open end facing away from the valve seat, a carriage having rods sliding in the guide and cross-heads interconnecting the rods on opposite sides of the guide, a piston mounted on one cross-head to cooperate with said cylinder and a valve on the other cross-head to cooperate with said seat, and means interconnecting the valve with the other cross-head to permit universal movement of the valve relatively to its seat, said means comprising a pin in aligned openings in the valve and cross-head, the openings in one part being larger than the pin and one part having an elongate recess extending transversely of the pin loosely to receive the other part.

Signed by me at Springfield, Massachusetts this 18th day of April 1929.

HAROLD WESSION.
